UNITED STATES PATENT OFFICE

OTTO SCHNEIDER, OF OBERKAUFUNGEN, GERMANY

ELECTRIC SWITCH

Application filed February 28, 1929, Serial No. 342,707, and in Germany April 10, 1928.

This invention relates to an electric switch provided with a spring-actuated lever arranged between a switch lever and a contact lever, the arrangement being such that this lever jumps quickly onward with a jerk when said spring-actuated lever has moved past the middle point of its path.

The characteristic features of the invention are these that, firstly, the spring-actuated lever is turnable on two pins supported in the base of the switch, whereas the switch lever is turnable on one of said pins and the contact lever is turnable on the other of the said pins, and that, secondly, a pin secured to the spring-actuated lever can engage on the one side a recess, which is provided in the switch lever, and the size of which suits to the extent of the movement of this lever, and can engage on the other side a similar recess provided in the contact lever. The spring pertaining to the spring-actuated lever is located and stretched out between the last-mentioned pin and a stationary point at the base.

Owing to this arrangement the spring actuated lever is moved along with the switch-lever when this latter commences to move, whereas the contact lever remains stationary at this time and is swung forwardly by the then expanded spring only after the spring-actuated lever has moved past the middle point of its path.

The invention is illustrated diagrammatically and by way of example on the accompanying drawing, on which Figure 1 shows a switch designed according to this invention partly in side-view and partly in vertical section, that is to say, the interior of the switch is shown in side-view, and a casing consisting of a base and a hood shown in vertical section, the switch being shown in closed position; Figure 2 is a vertical (or an axial) section through the switch, the plane of section being turned by 90° with respect to Fig. 1; Figure 3 is a plan of the switch, the hood being removed; and Figures 4 and 5 show the interior of the switch (as in Fig. 1) in two other positions, all as fully described hereinafter.

On the drawing, 1 denotes the base, and 2

and 3 are two projections thereon. 4 and 5 are two oppositely located lateral recesses in said projections, and form bearings for two pins 6 and 7 projecting forth from the two legs of the spring-actuated lever 8 which is designed as an inverted U. The legs of this lever are connected with one another near their upper ends by a transverse pin 9, to which is attached the upper end of a helical spring 10, the lower end of which is affixed to a transverse pin 11 embedded in a recess in the bottom face of the centre portion of the base, as shown in Fig. 2.

On the pin 7 is loosely movable the contact lever 12 which is of segmental shape, as shown in Figs. 1, 4 and 5, and to the circularly curved rim of which two U-shaped contact springs 13 and 14 are secured. This is effected by pins 15, 16, 17, and 18 in such a manner that the spring legs are capable of a certain lateral movement, viz. at right angles with respect to the plane of the lever or turnable plate 12.

The pin 6 which is located in the recess 4 of the projection 2, as already described, serves also as support for the switch-lever 19. The upper portion of this lever is bent in the manner shown in Fig. 2, and to this portion is affixed the grip 20 by means of a screw 21, said grip being located outside the hood 23 which covers and encloses all operating parts of the switch. In the uppermost portion of the hood is a slot 22 through which the shaft of the grip extends, and below this slot a plate 24 intended to prevent dust from entering into the interior of the switch through the slot is affixed to said grip shaft.

To the upper surface of the base 1 are secured four binding brackets 25, 26, 27 and 28, which are arranged in the manner shown in Fig. 3 and are connected with the wires pertaining to the circuit or circuits to be opened and closed by the switch.

The lever or turnable plate 12 is provided with a curved slot 30, and the switch-lever 19 is provided with a similar slot 29, and the transverse pin 9 of the spring-actuated lever 8 (which is the lever designed as an inverted U) extends with its projecting free ends into said two slots, the length of which

is determined with respect to the extent of the angular movement of the lever or plate 12 when changing its position (from that in Fig. 4 to that in Fig. 5, and reversely).

5 The manner of operation of the switch is as follows:

Supposing, the switch be in its switching-on position, as in Fig. 1, the ends of the U-shaped contact spring 13 will contact with 10 the binding brackets 25 and 27, and the ends of the transverse pin 9 will be located in the lefthand end of the slots 29 and 30 (the slot 29 pertaining to the switch lever 19, and the slot 30 pertaining to the contact lever 12, as 15 already described). When the switch lever is being moved to the right, first only the spring-actuated lever 8 is taken along with it, whereas the contact lever 12 remains in its position until the pin 9 has arrived in the 20 righthand end of the slot 30. While the lever 8 has thus been turned, the spring 10 has been expanded, and as soon as this lever has been moved past the middle point of its path the expanded spring becomes active, in consequence 25 whereof the other end of the pin 9 contacts with the righthand end of the slot 30 of the contact lever 12, and this latter is now suddenly turned from the position Fig. 4 into the position Fig. 5 so that the free ends 30 of the U-shaped spring 14 engage the binding brackets 26 and 28, thus closing this contact whereas the other contact (at the binding brackets 25 and 27) is now open.

Turning the movable parts back into their 35 former position proceeds in accurately the same manner, but, of course, in the reverse direction. I think I may abstain from entering into details in that respect.

I claim:

40 1. An electric switch, comprising, in combination, a base; a lever forming an inverted U; pins provided at the legs of this lever and engaging recesses of said base; a switch lever supported on one of said pins and adapted 45 to be actuated from the outside of the switch and having a slot; a segment-shaped contact lever supported upon the other of said pins and having also a slot; a spring connected at one end with said base and at the other end 50 with the first-mentioned lever and being so arranged with respect to it as to be able to cause it to jump quickly from one end position into the other end position; lateral projections at the said first-mentioned lever, 55 these projections engaging said slots, substantially as set forth.

2. An electric switch, comprising, in combination, a base; a lever forming an inverted U; pins provided at the legs of this lever and engaging recesses of said base; a switch lever supported on one of said pins and adapted to be actuated from the outside of the switch and having a slot; a segment-shaped contact lever supported upon the other of said pins 60 and having also a slot; a spring connected

at one end with said base and at the other end with the first-mentioned lever and being so arranged with respect to it as to be able to cause it to jump quickly from one end position into the other end position; and a transverse pin located in the said first-mentioned lever and having projecting ends engaging said slots, substantially as set forth.

In testimony whereof I affix my signature.
